UNITED STATES PATENT OFFICE.

MAY L. SOLOMONS, OF NEW YORK, N. Y.

DESIGN FOR A HATBOX.

Application filed October 4, 1924. Serial No. 10,963. Term of patent 7 years.

To all whom it may concern:

Be it known that MAY L. SOLOMONS, a citizen of the United States, and resident of the city of New York, in the county of New York and State of New York, has invented a new, original, and ornamental design for Hatboxes, of which the following is a specification, reference being had to the accompanying drawing, forming part thereof, in which—

Fig. 1 is a perspective view of a hat box embodying my new design; and

Fig. 2 is a development of the side walls thereof.

I claim:

The ornamental design for a hat box as shown and described.

Dated New York city, October 2, 1924.

MAY L. SOLOMONS.
